HOUSING FOR A WRITING INSTRUMENT

Helmut Bross, Weichselgartenstrasse 40,
Altenberg, Germany

Filed Aug. 30, 1965, Ser. No. 86,766

Claims priority, application Germany Mar. 4, 1965

Term of patent 14 years

(Cl. D74—17)

FIG. 2

FIG. 1

FIG. 3

FIG. 5

FIG. 4

FIG. 6

FIGURE 1 is a side view of a housing for a writing instrument showing by new design;

FIGURE 2 is a front view thereof;

FIGURE 3 is a rear view;

FIGURE 4 is an enlarged top plan view of FIGURE 1; FIGURE 5 is an enlarged sectional view taken on the line 5—5 of FIGURE 1; and

FIGURE 6 is an enlarged sectional view taken on the line 6—6 of FIGURE 1.

The essential features of my design reside in the portions shown in solid lines on the drawings.

I claim:

The ornametal design for a housing for a writing instrument, as shown and described.
